PRESSING MACHINE AND CONTROL
MECHANISM THEREFORGeorge W. Johnson, Cincinnati, Ohio, assignor to
The American Laundry Machinery Company,
Cincinnati, Ohio, a corporation of OhioApplication April 13, 1931, Serial No. 529,694
Renewed September 28, 1934

8 Claims. (Cl. 121—38)

My invention relates to pressing machines and, particularly, to a control mechanism therefor.

The invention is particularly applicable to a pressing machine of the scissors type which is operated by fluid pressure but may be applied to other presses and the object of the invention is to provide two hand control means for the pressing machine wherein both hand operated controlling means must be held in an operated position, 10 in this instance depressed, until the head of the press comes in contact with the buck, or very nearly so, at which time the two controlling means are freed or unlocked by movement of the pressing mechanism whereupon they may be further actuated to a locked position to cause a final 15 pressure between the head and buck regardless of whether or not manual pressure is maintained on the control means. However, the press is so constructed that final pressure can be obtained 20 without moving the control means to locked position by maintaining manual pressure thereon but when the control means are released the pressure in the operating cylinder will be released 25 and the press will open unless the control means are actuated to locked position.

The hand control means take the form of hand operated levers arranged to control valves connected in series in the fluid pressure supply line so that if either valve is permitted to close by 30 releasing manual pressure on the hand lever before the lever is moved to its extreme depressed and locked position and before the head contacts with the buck, the flow of fluid pressure to the operating cylinder will be cut off and the head 35 will immediately move upward to its normal or unoperated position. However, if the head is under final pressure against the buck with both hand levers locked down, the head will remain in such position until one of the hand operating 40 levers is shifted from its depressed position, or in other words, moved upwardly.

Various other objects and advantageous features of my invention will be seen in the following description and one embodiment thereof may be seen in the accompanying drawings wherein 45 similar characters of reference designate corresponding parts, and wherein:

Fig. 1 is a side view of a pressing machine constructed in accordance with my invention and the control mechanism therefor illustrating the hand operable lever mechanism for controlling the operation of the pressing machine; Fig. 2 is a sectional view of one of the valves for controlling the operation of the pressing machine 50 and showing the parts in one control position;

Fig. 3 is a view similar to Fig. 2 but showing the parts in another control position; Fig. 4 is a view similar to Fig. 1 and showing a modified form of means for controlling the operation of the pressing machine control means by movement of the pressing members into pressing engagement; Fig. 5 is a view similar to Fig. 2 but likewise showing the modified form of holding means for the pressing machine control and showing the pressing machine control means in one position; Fig. 6 is 10 a view similar to Fig. 5 but showing the pressing machine control means in another control position; and Fig. 7 is a diagrammatic view showing the manner of interconnecting the valves and motor of Figs. 1-3.

Referring to the drawings, I have shown a pressing machine consisting of a frame 1 having an upwardly extending portion 2 on which is pivotally mounted a head lever or pressure arm 3. A bed 4 on the frame 1 supports a lower 20 pressing member or buck 5 that is covered by the usual padding and the head lever or pressure arm 3 carries an upper pressing member 6 to which heat may be supplied in the well known manner. Springs 8 are connected at their upper 25 ends to the rearwardmost end 9 of the head lever 3 and at the lower ends to the machine frame. Such springs tend to maintain the head lever or pressure arm 3 in the open positions shown in Figs. 1 and 4 and to move the head lever to 30 such position. That is, the springs tend to maintain the pressing members 5 and 6 in separated relation, the distance of separation being such as to permit convenient access to the lower pressing member or buck 5 for the arrangement of 35 the work to be placed thereon.

The means for moving the upper pressing member 6 into engagement with the lower pressing member or buck 5 against the resistance of the springs 8 consists of a fluid pressure operated mechanism adapted to move the head lever or pressure arm 3 through the medium of a toggle mechanism comprising an upper link member 10 having one end thereof pivotally connected to the head lever or pressure arm 3 and a lower 40 link member 11 having one of its ends pivotally connected to the frame 1 as at 12, the free ends of the link members 10 and 11 being pivotally connected together as at 13.

The rearward end of a piston rod 14, connected 50 to a piston 15 in a cylinder 16 mounted on pins 18 and free to oscillate thereabout at the other of its ends, is pivotally connected as at 17 to the lower link member 11 a short distance below the 55 pivotal connection 13 between the free ends of

the link members 10 and 11 that obviously form a toggle mechanism. The purpose of connecting the piston rod 14 at such point is to permit an increased separation between the pressing members 5 and 6 by a shorter throw of the piston and piston rod. What has thus far been described is old and well known in the art.

In accordance with my invention, the flow of fluid pressure through a pipe 19 to the cylinder 16 whereby the piston and piston rod will be moved rearwardly to swing the links 10 and 11 of the toggle mechanism towards straight line position and move the head lever 3 about its pivot 20 and the head 6 into engagement with the bed or buck 5, and the exhaust of fluid pressure from such cylinder whereby the parts may be moved to unoperated position by the springs 8, is controlled by two duplex valves 21 that are connected in series in such manner that if either of the two valves is closed no fluid pressure will flow through the pipe 19. The pipe 19 is connected to the outlet of one of the valves 21, the inlet to this valve being connected to the outlet of the other valve 21 by means of a pipe 22, and the inlet of this last named valve is connected to a suitable source of supply of fluid pressure by means of a pipe 23. Such valves 21 are positioned in spaced relation at the front of the usual pressing table 24 whereby the use of both of the operator's hands is necessary to operate both of the valves.

The normal position of the pressing machine is open position, or with the head 6 spaced from the bed or buck 5 as shown in Figs. 1 and 4, in which position the proper garment lay is made on the pressing bed or buck 5. Then, both levers 32 are depressed which permits fluid pressure to flow through the pipe 19 into the cylinder 16 to bring the head 6 downwardly towards the bed or buck 5 as hereinbefore described. Suitable stops in the form of pivoted bars 34 mounted on a rock shaft 34' are provided to prevent the hand levers 32 being moved downwardly below their middle position manually until the pressing head and bed are substantially in engagement, the stops being such that they must be moved out of the path of the levers before the levers can be moved to their down positions. Such movement of the stops 34 is timed to take place simultaneously with the contacting of the head 6 with the pressing bed or buck 5 by means of a connecting rod 35 which has one end pivotally connected as at 36 to the free end of one of the stops 34 and slides freely adjacent its opposite end through a perforation provided in a laterally extending boss 37 provided on the link 10 that forms a part of the toggle mechanism. Suitable abutments 38 and 39 are provided on the rod 35 to be alternately contacted with by the boss 37 to move the stops 34 into and out of the path of the levers 32. When the stops 34 are moved out of the path of the levers such levers may be manually moved downwardly below the middle position whereupon they will be yieldingly held in such position by the springs 33 as shown in Fig. 3.

Each duplex valve 21 comprises an inner chamber 25, a fluid pressure inlet valve 26, and an exhaust valve 27 as shown in Figs. 2, 3, 5 and 6. The inlet valve 26 controls the flow of fluid pressure into the chamber 25 from the supply line 23 and the exhaust valve 27 controls the exhaust of fluid pressure from the chamber 25 to the atmosphere. In operation, it is not desirable to have the two valves 26 and 27 open at the same time

and for this reason the valves are interlocked by means of a walking beam 28 to which the valve stems are connected by means of links 29. Such walking beam 28 is pivotally mounted as at 30 to a bracket 31 that forms an integral part of the valve housing 21 and has one of its ends extended forwardly in the form of a hand lever 32 which is arranged to be placed in any of three positions, namely, up position as indicated by dotted lines in Figs. 2 and 5, middle position as shown by the full lines in Figs. 2 and 5 and extreme depressed position as shown in Figs. 3 and 6.

As a means for holding the lever 32 in its extreme up or down positions, the hand lever is provided with a past-center snap mechanism which is so arranged that the lever 32 will be yieldingly held in its extreme up or down position after being manually moved thereto and, at the same time, is so arranged as to always tend to move the hand lever upwardly from the middle position hereinbefore described whereby the lever must be manually maintained in this position. This means consists of a rod 33' pivotally mounted at one end at the connection between the walking beam 28 and the link 29 leading to the valve 26, and having its free end slidably mounted in an opening in an oscillatable member 33'' carried by the machine frame. The spring 33 is interposed between the oscillatable member 33'' and the connection between the rod 33' and the walking beam 28. With this construction it will be seen that after the hand lever 32 is moved toward its down position the pivots 30, 35' and the oscillatable member 33'' are moved toward a position wherein the pivots and the oscillatable member are all in the same straight line as the pivot 35', with the spring 33 reaching its highest point of compression at this time. Then, movement of the pivot 35' above or below its position of alignment with the pivot 30 and oscillatable member 33'' will result in the spring 33 being effective to move the hand lever 32 to its extreme up or down position and resiliently hold it there. In Figs. 2, 3, 5 and 6, it will be noted that the hereinbefore described middle portion of the hand lever 32 does not move the pivot 35' entirely into the alignment just described but the pivot 35' is substantially below this line whereby release of manual pressure on the hand lever 32 will result in the hand lever being snapped towards extreme up position.

As shown, when the hand lever 32 is in its up position the inlet valve 26 is closed and the exhaust valve 27 is open, when the hand lever is in its middle position the inlet valve 26 is open and the exhaust valve 27 is closed, and when the hand lever is in its down position the inlet valve 26 is open and the exhaust valve 27 is closed. Thus, it will be noted that the valves 26 and 27 are in substantially the same operative position when the lever 37 is in its middle as when it is in its down position, the only difference being that the lever is held manually in its middle position and yieldingly held by the spring 33 when in its down position.

Since the valve 27 is closed against its seat when the lever 32 is in its middle position, one of its links 29 is provided with a lost motion connection in the form of a slot 40 to permit the lever 32 to be moved to its lowermost position as shown in Figs. 3 and 6. A spring 41 is provided to normally tend to close the valve 27 and hold it in closed position.

In the operation of this control means, assuming that the pressing machine is in its normal

position or with the pressing head separated from the pressing bed or buck as shown in Figs. 1 and 4, the proper garment lay is made on the pressing bed or buck 5 and both hand levers 32 are moved 5 to the central position shown in Figs. 2 and 5 which will permit the exhaust valve 27 to close under the action of the spring 41 and move the inlet valves 26 to open position whereby fluid pressure will flow through the pipe 23, past the 10 valve 26, through the pipe 22, through the other valve 21, and through the pipe 19 to the cylinder 16 to move the piston 15 forwardly to close the press and bring about the pressing action. On the press closing, the stops 34 are moved out of 15 their normal position shown in Figs. 2 and 5 wherein they limit their downward movement of the handles 32 to the position shown in Figs. 3 and 6 whereupon the handles 32 may be moved to extreme depressed position with the past center 20 springs 33 yieldingly locking the handles in this down position with the exhaust valves closed and the inlet valves open. Continuous pressure may thus be had between the pressing head and the pressing bed or buck with the manual pressure 25 released from the handles 32. After the pressing operation is completed, one of the handles 32 may be moved upwardly to open one of the exhaust valves whereupon the fluid pressure will exhaust from the cylinder 16 and the press will be opened 30 under the action of the springs 8. However, both of the handles 32 must be moved upwardly against the past center resistance of the yielding locating means to return the valves to their normal unoperated position, the spring 33 being somewhat 35 stronger than the springs 41 which normally tend to hold the exhaust valves closed. This upward movement is accomplished automatically by the stops 34 being moved to lift levers 32 by the lug 37 engaging stop 38 on rod 35.

40 Referring to Figs. 4, 5 and 6 of the drawings, I have shown a modified form of my invention wherein the stops 34 are moved to inoperative position by means of a small cylinder 42 containing a piston 43 which is normally held in the 45 position shown in Fig. 5 by means of a spring 44. The piston rod 45 is operatively connected to the free end of one of the stops 34 as at 46 by means of a link 47, the piston, piston rod, and stops 34 being yieldingly held in operative position by 50 means of the spring 48. When fluid pressure is admitted to the cylinder 42 through a pipe 48 the stops 34 will be moved out of the path of the levers 32 against the resistance of the spring 44 by movement of the piston in the well known manner. 55 Such pipe 48 connects the cylinder 42 to the cylinder 16, the connection to the cylinder 16 being located in such position that fluid pressure from the cylinder can not enter the pipe 48 and cylinder 42 until the piston 15 has moved a sufficient 60 distance to move the pressing head 6 into engagement with the pressing bed or buck 5. This is conveniently done by locating the connection of the pipe 48 with the cylinder 16 at a point beyond which the piston 15 will have passed when the 65 head 6 contacts with the pressing bed or buck 5.

In the operation of this modified form of apparatus, to return the head 6 to its normal up position, either one of the hand levers 32 is manually moved upwardly which will close one inlet valve 26 and open one exhaust valve 27 so that the fluid from within the cylinder 16 is free to exhaust to the atmosphere past the valve 27 and the 70 springs 8 will be effective to return the parts to their normal unoperated position. Then, when the piston 15 in the cylinder 16 has moved to the

left past the point where the pipe 48 is connected to the cylinder 16, the fluid within the cylinder 42 is free to exhaust to the atmosphere through the right-hand end of the cylinder 16 past the piston rod 14 which is made loose fitting through the cylinder and whereupon the spring 44 will return the stops 34 into the path of the levers 32. Such movement of the stops 34 will also return to their up position manually to their middle position whereupon the yielding locking means 33 will return the levers to their extreme upper position. 10

With the above construction, I have provided a pressing machine and particularly a control mechanism therefor of such nature that the danger of an operator's hand being caught between the pressing head and the pressing bed during the operation of the pressing machine is practically eliminated. This is due to the fact that the control mechanism embodies spaced control 15 means requiring the use of both of the operator's hands thereon until the pressing members are either brought entirely or at least substantially into pressing engagement. However, the control means is such that it may be operated after the 20 pressing members have been brought into or substantially into pressing engagement to maintain the pressing members in pressing engagement without necessitating the use of the operator's hands thereon. A further advantage resides in 25 the fact that automatic operated locking means are provided for preventing the operation of the control means into this pressure holding position until after the pressing members are either entirely in or substantially in pressing engagement. 30 However, if desired, the control means may be manually held in such position as to cause final pressure between the pressing members. 35 Various other advantageous features will be readily apparent.

40 What I claim is:

1. A pressing machine, comprising relatively movable head and bed members, operating mechanism therefor, and control means for said mechanism, including spaced hand controls movable 45 from inoperative to an intermediate position to produce operation of said mechanism and engagement approach movement of said members, and to a full operated position to maintain said members in engagement, separate means normally tending to move each of said hand controls from intermediate to inoperative position, and means governed by the relative position of said movable members for controlling movement of said hand controls from intermediate to full operated 50 position.

2. A pressing machine, comprising relatively movable head and bed members, operating mechanism therefor, and control means for said mechanism, including spaced hand controls movable 60 from inoperative to an intermediate position to produce operation of said mechanism and engagement approach movement of said members, and to a full operated position to maintain said members in engagement, means normally tending to 65 move said hand controls from intermediate to inoperative position, and means governed by the relative position of said movable members for controlling movement of said hand controls from intermediate to full operated position, said control 70 moving means being effective to maintain said controls in full operated position on movement thereto.

3. A pressing machine, comprising relatively movable head and bed members, operating mech- 75

- anism therefor, and control means for said mechanism, including spaced hand controls movable from inoperative to an intermediate position to produce operation of said mechanism and engagement approach movement of said members, and to a full operated position to maintain said members in engagement, means normally tending to move said hand controls from intermediate to inoperative position, and means governed by 5 the relative position of said movable members for controlling movement of said hand controls from intermediate to full operated position, said control moving means being effective to move said controls from a point of operation between said 10 intermediate and full operated position to full operated position and maintain the controls therein.
4. A pressing machine comprising relatively movable head and bed members, operating mechanism therefor, and control means for said mechanism, including spaced hand controls movable from inoperative to an intermediate position to produce operation of said mechanism and engagement approach movement of said members, and to a full operated position to maintain said members in engagement, spring actuated toggle means normally tending to move said hand controls from intermediate to inoperative position, and means governed by the relative position of 15 said movable members for controlling movement of said hand controls from intermediate to full operated position.
5. A pressing machine, comprising relatively movable head and bed members, operating mechanism therefor, and control means for said mechanism, including spaced hand controls movable from inoperative to an intermediate position to produce operation of said mechanism and engagement approach movement of said members, and to a full operated position to maintain said members in engagement, spring actuated toggle means normally tending to move said hand controls from intermediate to inoperative position, and means governed by the relative position of 20 said movable members for controlling movement of said hand controls from intermediate to full operated position.
6. A pressing machine, comprising relatively movable head and bed members, operating mechanism therefor, and control means for said mechanism, including spaced hand controls movable from inoperative to an intermediate position to produce operation of said mechanism and engagement approach movement of said members, and to a full operated position to maintain said members in engagement, spring actuated toggle means normally tending to move said hand controls from intermediate to inoperative position, and means governed by the relative position of 25 said movable members for controlling movement of said hand controls from intermediate to full operated position.
7. A pressing machine, comprising relatively movable head and bed members, operating mechanism therefor including a fluid pressure actuated motor, and control means for said mechanism comprising spaced valves connected in series between said motor and a source of fluid supply, manuals controlling said valves and movable from inoperative to an intermediate position to 30 produce operation of said mechanism and engagement approach movement of said members, and to a full operated position to maintain said members in engagement, means normally tending to move said manuals from intermediate to inoperative position, and means governed by the relative position of 35 said movable members for controlling movement of said manuals from intermediate to full operated position.
8. A pressing machine, comprising relatively movable head and bed members, operating mechanism therefor, and control means for said mechanism, including spaced manuals movable from inoperative to an intermediate position to produce operation of said mechanism and engagement approach movement of said members, and to a full operated position to maintain said members in engagement, means normally tending to move said manuals from intermediate to inoperative position, stop means for each manual, and means connecting said stop means with said operating mechanism for positioning said stop means against movement of its associated manual to 40 full operated position except when said head and bed members are safely closed.

GEORGE W. JOHNSON.
